UNITED STATES PATENT OFFICE

2,449,711

DOOR LOCK

Joseph H. Milligan, Framingham, Mass.

Application May 24, 1945, Serial No. 595,510

11 Claims. (Cl. 70—215)

1

This invention relates to door locks and especially to that type of door lock in which one of the door knobs, usually the outer door knob, has a lock mechanism incorporated therein and is normally locked from turning movement but can be unlocked by means of a key so that it can be turned to withdraw the door latch when the door is to be opened.

In doors having door knobs for opening the door the two knobs are commonly mounted on a flat sided spindle which extends through the door and which carries a collar having arms that co-operate with fingers with which the door latch is provided, so that when either knob is turned the resultant turning movement of the spindle operates to withdraw the door latch.

It is one of the objects of my present invention to provide a novel door lock of the above-mentioned type which can be readily substituted for the ordinary pair of knobs and spindle of any door without making any important alteration in the door itself, whereby a door which is provided with door knobs but not provided with a lock can be easily converted into a door having a door lock which can be unlocked by the use of a key.

Another object of the invention is to provide a door lock of this type with means by which a person on the inside of the door may set the lock in the outside knob so that turning movement of said outside knob will be ineffective to withdraw the door latch, thereby making it impossible for a person on the outside to open the door even though he has the proper key.

A further object of the invention is to provide a novel means whereby the lock can be set from the outside so that the outside knob will remain unlocked and can, therefore, be turned to withdraw the door latch without the use of a key.

Further objects of the invention are to provide various novel features relating to door locks of this type which will be more fully hereinafter set forth and then pointed out in the claims.

In the drawings wherein I have illustrated a selected embodiment of my invention,

Fig. 1 is a fragmentary section of a door having a door latch and showing the outside knob in end view;

Fig. 2 is a section on the line 2—2, Fig. 1;

Fig. 3 is a section on the line 3—3, Fig. 1;

Fig. 4 is a section on the line 4—4, Fig. 1;

Fig. 5 is a section on substantially the line 5—5,

Fig. 6 is a section on the line 6—6, Fig. 7;

Fig. 7 is a section on the line 7—7, Fig. 2;

Fig. 8 is a section on the line 8—8, Fig. 2;

Fig. 9 is a section on the line 9—9, Fig. 3;

Fig. 10 is a perspective view of the knob-supporting member for the outer knob;

Fig. 11 is a longitudinal section through the knob-supporting member;

2

Fig. 12 is a sectional view on the line 3—3, Fig. 1 showing the position of the parts when the spindle has been unclutched from the outer knob.

Fig. 13 is a perspective view of the plate secured to the inner knob and which forms part of the means for unclutching the spindle from the outer knob when the inner knob is turned.

Fig. 14 is a perspective view of the supporting member carried by the spindle on which the inner knob is mounted.

Figs. 15 and 17 are fragmentary sectional views illustrating the parts for unclutching the spindle from the outer knob when the inner knob is turned.

Fig. 16 is a section on the line 16—16, Fig. 12.

Fig. 18 is a fragmentary sectional view showing the means for returning the outer knob to its central position.

In the drawings 1 indicates a portion of a door which is equipped with the usual spring-pressed door latch 2, the latter having a body portion 3 which is received within a housing 4 that is set into a recess 5 with which the door is provided, the front plate 6 of the housing having an opening through which the nose 7 of the door latch projects. The body of the door latch is provided with two rearwardly extending arms 8 having at their ends inturned fingers 9 that co-operate with arms 10 formed on a collar 11 that is provided with a square hole and is mounted on the square spindle of the door knob structure so that when either knob is turned, the resultant turning movement of the spindle will turn the collar 11 and will, through the co-operation of either arm 10 and its co-operating finger 9, withdraw the door latch 2 against the action of a spring 12 which normally holds the latch yieldingly in its projected position.

This type of door latch is one which is commonly used. As stated above my invention involves a pair of knobs having a door lock incorporated therein and a spindle associated therewith, which knobs and spindle can be substituted for an ordinary pair of knobs in a door having the door latch above described, thereby converting the door into one which can be locked and which requires the use of a key for unlocking it.

In the device herein illustrated the outside knob of the door is indicated at 13, and the inside knob at 14. These two knobs are connected by a square sided spindle 15 which extends through the door and through the square opening in the collar 11.

The outside knob 13 is mounted on a stationary knob supporting member 16 which is stationarily secured to the door 1. This knob-supporting member has an inner portion 17 of large diameter and an outer portion 18 of smaller diameter. The knob-supporting member may be stationarily attached to the door 1 in any approved way.

As herein shown the inner end of the knob-supporting member has secured thereto by means of screws 19 an attaching disk 20 which is provided with two attaching lugs 21. Secured to the door 1 by means of screws 22 is an anchoring plate 23 that is provided on its outer face with a recess 24 adapted to receive the attaching disk 20. The anchoring disk 23 is provided with two openings 25 adapted to receive the studs 21, each stud being cut away on one side to provide a notch 26. In securing the knob-supporting member 16 to the door, the studs 21 are entered through the openings 25 in the anchoring plate 23 and then the knob-supporting member is turned slightly about its axis to bring the edges of the openings 25 into the notches 26, and thereby the knob-supporting member will be firmly secured to the anchoring plate 23. The door itself may be provided with a recess 27 to accommodate the inner ends of the studs 21 as shown in Fig. 4.

The attaching plate 20 is provided with a radially extending spring-pressed locking pin 28 which is backed by a spring 29 and which is adapted to enter a recess 30 with which the anchoring plate 23 is provided, thereby locking the knob-supporting member 16 from turning movement after it has been properly assembled with the anchoring plate 23. The flange of the outer knob that encloses the attaching plate 20 is provided with an aperture 31 through which a wire may be inserted to disengage the locking pin 28 from the recess 30 when it is desired to remove the knob-supporting member 16 and the outer knob 13.

The outside knob 13 is provided with a central cylindrical chamber 32 having a diameter the same as that of the larger portion 17 of the knob-supporting member 16, which larger portion occupies the inner end of said chamber 32. Situated within the chamber 32 at the outer end of the knob is a barrel element 33 which is provided with a central opening 34 of a size to fit the smaller portion 18 of the knob-supporting member. This barrel element 33 is secured in place by means of a screw 134 which extends through the barrel from the inner end, and the outer end of which screw has screw-threaded engagement with a nut 35 carried by the knob. The barrel element 33 is thus rigidly secured to the knob and practically forms a part thereof.

The outside knob 13 is connected to the spindle 15 through the medium of a clutch device which is normally engaged but which can be disengaged from the inside of the room, as will be presently described.

The outer end of the spindle 15 is formed with a flange 36 that is received in an axial recess 40 with which the knob-supporting member 16 is provided. Projecting from the flange 36 are two pins 37 which extend through a clutch flange 38 that is also received in said recess 40. The clutch flange 38 has a clutch pin 39 extending outwardly therefrom which passes through an arcuate opening 90 formed in the larger portion 17 of the knob-supporting member 16 and the extremity of which is adapted to engage in a clutch recess 41 with which the inner face of the barrel member 33 is provided. When the parts are in their operative position shown in Figs. 2 and 3 with the clutch pin 39 occupying the recess 41, turning movement of the knob 13 on the knob-supporting member will operate through the clutch pin 39, clutch disk 38, pins 37 and flange 36 to turn the

flat sided spindle 15, thereby to turn the collar 11 and withdraw the door latch 2.

The outer knob 13 is normally locked to the stationary knob-supporting member 16 so that the knob cannot be turned, but the knob can be unlocked from said knob-supporting member to permit it to be turned by means of a suitable key. For this purpose the barrel element 33 is provided with a radial opening 43 into which is received a radially extending locking pin 42 that is backed by a spring 44. The inner end of this locking pin 42 is adapted to engage in a recess 45 with which the portion 18 of the knob-supporting member is provided, and when the locking pin is in its normal position shown in Figs. 2 and 7, the knob 13 will be locked from turning movement.

The barrel element 33 is provided with an opening in which is received a key plug 46 having a key slot 47 therein. Said plug and barrel element are provided with the usual set of tumbler and follower pins (not shown) which normally lock the plug 46 from turning movement but which become lined up to free the plug when a key is inserted into a key slot 47 as usual in so-called "Yale" locks.

The plug 46 is provided on one side with a shoulder 48 adapted to engage the inner end of a pin 49 that is slidably mounted in the barrel element 33. The locking pin 42 is formed at its outer end with a head 50 having a portion overlying the pin 49.

When a proper key is inserted into the key slot 47 the tumbler and follower pins will be lined up and the plug 46 will be freed for turning movement. The turning of the plug by the key in a counterclockwise direction, Fig. 7, will operate through the shoulder 48 to raise the pin 49 and thereby lift the locking pin 42 against the action of its spring 44 and out of engagement with the portion 18 of the knob-supporting member, thereby unlocking the knob and freeing it for turning movement. When the knob is thus unlocked, the turning movement thereof will operate through the clutch pin 39, clutch disk 38, pins 37 and flange 36 to turn the spindle 15 and thereby withdraw the door latch 2. With my improvement the outer knob of the door will be normally locked so that it cannot be actuated but it can be unlocked by means of a suitable key to permit it to be turned and thereby to withdraw the door latch.

The inner knob 14 is so constructed that it can be operated to turn the spindle 15 and thus withdraw the door latch 2 even though the outer knob is locked, so that a person on the inside of the room can always open the door.

For this purpose means are provided whereby an initial turning movement of the inner knob 14 will disengage the clutch pin 39 from its socket 41 in the outer knob, thus freeing the spindle from the outer knob so it is free to turn, and further turning movement of the inner knob will then rotate the spindle 15 to withdraw the door latch 2.

Secured to the inner end of the spindle 15 is a supporting collar 51 which is inserted in a chamber 52 with which the inner knob 14 is provided, said collar 51 being secured to the spindle 15 by means of a suitable set screw 53.

The clutch disk 38 carrying the clutch pin 39 is mounted on the end of a stem 54 which extends through an axial bore 55 with which the spindle 15 is provided. The outer end of this bore is enlarged and receives a spring 56 which

acts against the clutch disk 38 and normally holds it in its operative clutching position.

The supporting collar 51 is provided with a plurality of through openings 58 extending parallel to the spindle, in each of which openings is received a thrust pin 57. The inner end of each opening 58 is counterbored, and the inner end of each thrust pin is enlarged to fit the counterbore as shown at 59. Situated in each counterbore is a spring 60 which normally tends to hold the thrust pin in its forward or inward position. The inner enlarged end 59 of each thrust pin is cone-shaped and is normally received in a V notch 61 formed in a plate 62 which is secured to the inner face of the inner knob 14 by suitable screws 99.

The plate 62 is provided with a boss 93 in the face of which the V notches 61 are formed. This boss is cut away at 93 to provide a space bounded by the two abutment walls 95 in which is received a projection 96 extending from the inner end of the supporting collar 51. The space between the abutment walls 95 is somewhat greater than the width of the projection 96, thereby providing a certain amount of loose play between the projection and the abutment walls 95, the purpose of which will be presently described.

The stem 54 extends through and beyond the end of the spindle, said projecting portion of the stem being screw threaded and having screw threaded thereto a thrust collar 63 which fits the chamber 52 of the knob 14 and is backed by a suitable spring 64. The spring 64 yieldingly holds the thrust collar 63 in engagement with the outer face of the supporting collar 51 as shown in Figs. 2 and 3. The thrust collar 63 is shown as having a reduced inner end 65 which fits within an axial recess in the outer end of the supporting collar 51.

Figs. 2 and 3 show the knobs 14 and the parts therein in normal position with the thrust collar 63 in engagement with the outer face of the supporting collar 51 and with the inner pointed ends of the thrust pins 57 occupying the notches 61.

With the parts in this position the clutch pin 39 will be in engagement with the notch 41 in the knob-supporting member 16, and the spindle 15 and the supporting collar 51 which is mounted thereon will thus be locked from turning movement.

When the inner knob 14 is turned, this turning movement is communicated to the plate 62 which is secured to the knob, and during the initial turning movement of the plate 62 the faces of the V notches 61 will have a camming action against the pointed ends of the thrust pins 57 and will thus force them backwardly, it being understood that the spindle 54, and consequently the supporting collar 51, is stationary at this time. This backward movement of the thrust pins is communicated to the thrust collar 63 which is screw threaded to the stem 54 and thus the thrust collar and stem will be moved to the right in Figs. 2 and 3, thereby moving the clutch collar 38 to the right and withdrawing the clutch pin 39 from its socket 41 as shown in Fig. 12. By this operation the spindle 15 is unclutched from the outer knob.

The lost motion between the projection 96 and the abutment walls 95 permits this initial turning movement of the knob 14 while the spindle is still locked from turning movement. By the time the knob has been turned to bring one of the walls 95 into engagement with the projection 96

on the supporting collar 51, the spindle will have been unclutched from the outer knob 13 and further turning movement of the inner knob 14 will operate through the engagement of one of the abutment walls 95 with the projection 96 to turn the spindle 15 and thereby withdraw the door latch 2.

When the inner knob 14 has been released and has been returned to its normal central position, the springs 64 and 66 co-operate to return the clutch disk 38 to its normal operative position shown in Fig. 3, thereby again clutching the outer knob 13 to the spindle 15. When the inner knob has again resumed its normal central position, the thrust pins 57 will be in line with the V notches 61 and the springs 60 will restore said thrust pins into their normal position shown in Fig. 2.

I have provided herein means for automatically returning the knob 14 to its normal position after it has been turned to retract the door latch and has been released. The plate 62 is provided with a projection 66 which is located between two spring-pressed followers 67 carried by the rose 68. This rose is provided with an arcuate slot 69 in which is received a return spring 70, the ends of which abut against the two followers 67. Said rose is also formed with two stops 71 to limit the spring-pressed movement of the followers.

When the inner knob 14 is turned in either direction, the projection 66 will engage one of the followers and will thus compress the spring 70 so that when the knob is released the expanding action of the spring will return it to its normal position.

My improved lock is also provided with means whereby a person on the inside of the door can disengage the clutch pin 39 from its socket 41 and lock the clutch in its disengaged condition, thereby making it impossible for anyone to open the door from the outside even though he has the proper key. Screw threaded to the end of the stem 54 is a nut 75 having a head portion 76 which projects beyond the knob 14 so that a person can readily grasp said nut. By pulling backwardly on the nut, the stem 54 and clutch disk 38 is moved to the right, Figs. 1 and 2, thereby disconnecting the clutch pin 39 from its socket 41.

The knob 14 is provided with a spring-pressed locking pin 77 which engages the nut 75 and the latter is formed with a recess 78 in one side at its inner end adapted to receive the locking pin 77 when the knob is pulled inwardly as shown in Fig. 12. When a person on the inside of the room desires to make it impossible for a person to enter the room from the outside, he will pull outwardly on the nut 75, thus disengaging the clutch pin 39 from its socket 41 and when the nut 75 has been thus withdrawn, the locking pin 77 snaps into the recess 78, thereby locking the stem and the clutch disk 38, in their retracted position. So long as the clutch pin remains in its retracted position, the outer knob 13 will be disengaged from the spindle 15 so that even if a person unlocks the outer knob 13 with the proper key, yet the turning movement of the unlocked knob will not be communicated to the spindle and the knob will simply turn freely on the knob-supporting member 16.

The side walls of the notch or recess 78 are inclined so that if the inner knob 14 is turned while the locking pin 77 is occupying the notch 78, the inclined side faces of the notch will cam

the locking pin 17 backwardly, thereby releasing the nut 15 and allowing the stem 54 with its clutch disk 38 to move back into its normal operative position under the influence of springs 56 and 64.

I have also provided herein means whereby a person on the outside of the door can set the lock for the outside knob 13 in an inoperative position so that a person can turn the outside knob 13 to open the door without the use of a key. Slidably mounted in the outer knob 13 is a plunger 80 from which extends an arm 81 having at its end an inclined face 82 that is adapted to engage the underside of the head 50 of the locking stem 42 when the plunger 80 is pushed inwardly, thereby holding said head 50 raised. When therefore the head 50 has been raised by inserting a key in the key slot 47 and turning the plug 46, thus unlocking the outside knob 13, and said plunger 80 is pushed inwardly to move the face 82 of the arm 81 underneath the raised head 50, said arm 81 will hold the head 50 raised and thus hold the outer knob in an unlocked condition. The plunger 80 is provided with two notches 83 which co-operate with a spring-pressed locking pin 84 to retain said plunger in either its normal or its inward position.

The knob 13 is also provided with a restoring plunger 85 which is situated at right angles to the plunger 80 and which is constructed so that when the restoring plunger is pushed downwardly it will restore the plunger 80 to its normal position. The restoring plunger 85 is normally held in its raised position by means of a spring 86, and the construction is such that when the restoring plunger 85 is depressed, it will engage the cam face 96 on the plunger 80 and will move the latter backwardly into its normal position.

Whenever it is desired to leave the door unlocked so that it can be opened without the use of a key, the plunger 80 will be pushed inwardly, thereby raising the locking pin 42 out of engagement with the portion 18 of the knob-supporting member, and so long as the plunger 80 remains in its inward position, the knob will remain unlocked so that the door can be opened from the outside without the use of a key.

By simply depressing the restoring plunger 85 the plunger 80 will be restored to its normal position, thus allowing the spring 44 to return the locking pin 42 to its locking position.

In Fig. 18 I have shown means which may be employed for returning the outer knob to its central position after it has been turned. For this purpose, the outer knob 13 is provided on its inner face with a projection 88 which enters an annular groove 91 formed in the attaching plate 23a which is secured to the door 1. Located within this annular groove 91 is a spring 90, the ends of which engage two followers 89 between which the projection 88 is located. The attaching plate 23a is shown as provided with two stop shoulders 71 which limit the spring impelled movement of the followers 89.

When the knob 13 is turned in either direction, the projection 88 thereon will engage one of the followers and will thus compress the spring 90 so that when the knob is released, the expanding action of the spring 90 will return said knob to its initial or central position.

I claim:

1. A door knob structure for a door having the usual door latch, said door knob structure comprising a knob-supporting member, means sta-

tionarily securing said member to the outside of the door, an outer knob mounted on said knob-supporting member, a key-actuated locking means for normally locking the outer knob to the knob-supporting member, a latch-actuating spindle adapted to extend through the door and to be operatively coupled to the door latch, means separate from said key-actuated locking means for normally connecting the spindle to the outer door knob, whereby turning movement of the knob when unlocked will turn the spindle, an inner door knob mounted on and connected to the spindle on the inside of the door and by which the spindle may be turned, and means operative from the inside of the door to disconnect said spindle from the outer knob thereby releasing said spindle for turning movement by the turning movement of the inner knob and simultaneously rendering the outer knob, when unlocked, ineffective to turn the spindle.

2. A door knob structure for a door having the usual door latch, said door knob structure comprising a knob-supporting member, means stationarily securing said member to the outside of the door, an outer knob mounted on said knob-supporting member, a key-actuated locking means for normally locking the outer knob to the knob-supporting member, a latch-actuating spindle adapted to extend through the door and to be operatively coupled to the door latch, means separate from said key-actuated locking means for normally connecting the spindle to the outer door knob, whereby turning movement of the outer knob when unlocked will turn the spindle, an inner door knob mounted on and connected to the spindle on the inside of the door and by which the spindle may be turned, means operative from the inside of the door to disconnect said spindle from the outer knob thereby releasing said spindle for turning movement by the turning of the inner knob and simultaneously rendering the outer knob, when unlocked, ineffective to turn the spindle, and means to lock the spindle so disconnected.

3. A door knob structure for a door having the usual door latch, said door knob structure comprising a knob-supporting member, means stationarily securing said member to the outside of the door, an outer knob mounted on said knob-supporting member, a key-actuated locking means for normally locking the outer knob to the knob-supporting member, a latch-actuating spindle adapted to extend through the door and to be operatively coupled to the door latch, a clutch device separate from said key-actuated locking means for normally connecting the spindle to the outer knob, whereby turning movement of the outer knob when unlocked will turn the spindle, an inner door knob mounted on the spindle on the inside of the door, and means operative from the inner knob to disconnect said clutch device, thereby releasing the spindle for turning movement by the turning of the inner knob and simultaneously rendering the outer knob, when unlocked, ineffective to turn the spindle.

4. A door knob structure for a door having the usual door latch, said door knob structure comprising a knob-supporting member, means stationarily securing said member to the outside of the door, an outer knob mounted on said knob-supporting member and provided with a key slot, means normally locking the outer knob to the knob-supporting member, means actuated by a key inserted into the key slot to unlock the outer

knob from the knob-supporting member, a latch-actuating spindle adapted to extend through the door and to be operatively coupled to the door latch, means normally coupling said spindle to the outer knob, whereby turning movement of the unlocked outer knob will turn the spindle and thereby unlatch the door, an inner knob mounted on the spindle on the inside of the door and free for limited turning movement relative to the spindle, and means rendered operative by such limited turning movement of the inner knob to uncouple the spindle from the locked outer knob thereby releasing said spindle for turning movement by the continued turning of the inner knob.

5. A door knob structure for a door having the usual door latch, said door knob structure comprising a knob-supporting member, means stationarily securing said member to the outside of the door, an outer knob mounted on said knob-supporting member and provided with a key slot, means normally locking the outer knob to the knob-supporting member, means actuated by a key inserted into the key slot to unlock the outer knob from the knob-supporting member, a latch-actuating spindle adapted to extend through the door, a clutch normally connecting the spindle to the outer knob, whereby turning movement of the unlocked outer knob will turn the spindle and thereby unlatch the door said clutch including a clutch pin associated with the spindle and a pin-receiving recess with which said outer knob is provided, an inner knob mounted on the spindle on the inside of the door and free for limited turning movement relative to said spindle, and means rendered operative by such limited turning movement of the inner knob to withdraw the clutch pin from said recess and thereby release the spindle from the locked outer knob and free it to be turned by the inner knob.

6. A door knob structure for a door having the usual door latch, said door knob structure comprising a knob-supporting member, means stationarily securing said member to the outside of the door, an outer knob mounted on said knob-supporting member and provided with a key slot, means normally locking the outer knob to the knob-supporting member, means actuated by a key inserted into the key slot to unlock the outer knob from the knob-supporting member, a latch-actuating spindle adapted to extend through the door and to be operatively coupled to the door latch, means normally coupling said spindle to the outer knob, whereby turning movement of the unlocked outer knob will turn the spindle and thus unlatch the door, an inner knob mounted on the spindle on the inside of the door and free for a limited turning movement relative to the spindle, and means rendered operative by the initial turning movement of the inner knob to disconnect the spindle from the locked outer knob thereby releasing said spindle for turning movement by further turning movement of the inner knob.

7. A door knob structure for a door having the usual door latch, said door knob structure comprising a knob-supporting member, means stationarily securing said member to the outside of the door, an outer knob mounted on said knob-supporting member, releasable locking means normally locking said outer knob to the knob-supporting member, a latch-actuating spindle adapted to extend through the door, said spindle having an axial bore, an inner knob mounted on said spindle, a clutch element associated with

said spindle for turning movement therewith and normally having clutching engagement with the outer knob, a rod extending through the axial bore of the spindle and connected to said clutch element, said rod being operable from the inside of the door to disengage the clutch element from clutching engagement with the locked outer knob, thereby releasing the spindle for turning movement by the inner knob and simultaneously rendering the outer knob, when unlocked, ineffective to turn the spindle.

8. A door knob structure as described in claim 7 combined with latching means carried by the inner knob and co-operating with said rod to hold 15 the clutch element disengaged.

9. A door knob structure as in claim 7 combined with latching means carried by the inner knob and co-operating with the rod to hold the clutch element disengaged, and means to release 20 the clutching means by turning movement of the inner knob.

10. A door knob structure for a door having the usual door latch, said door knob structure comprising a knob-supporting member, means stationarily securing said member to the outside of the door, an outer knob mounted on said knob-supporting member, a latch-actuating spindle coupled to the outer knob and adapted to extend through the door and to be operatively connected to the door latch, locking means normally locking said outer knob to the knob-supporting member, key-actuated means to release said locking means, a depressible plunger carried by the outer knob, means associated with said plunger and operative when the latter is depressed to hold said locking means in released condition, and an inner knob mounted on said spindle on the inside of the door.

11. A door knob structure for a door having the usual door latch, said door knob structure comprising a knob-supporting member, means stationarily securing said member to the outside of the door, an outer knob mounted on said knob-supporting member, a latch-actuating spindle coupled to the outer knob and adapted to extend through the door and to be operatively connected to the door latch, locking means normally locking said outer knob to the knob-supporting member, key-actuated means to release said locking means, a depressible plunger carried by the outer knob, means associated with said plunger and operative when the latter is depressed to hold said locking means in released condition, an inner knob mounted on said spindle on the inside of the door, a second depressible plunger carried by the outer knob, and means actuated by the depression thereof to restore the first-named plunger to normal position.
